ROTARY-DRILL WELL BIT

Walter Andrew Abegg, Los Angeles, Calif., assignor to John Grant, Los Angeles, Calif.

Application April 29, 1937, Serial No. 139,756

6 Claims. (Cl. 255—71)

My invention relates to rotary drill well bits wherein the cutters are in the form of revolving elements having teeth adapted to abrade and cut away the material to be removed from the 5 hole.

The axis of the main cutting element is inclined with respect to the vertical axis of the 10 drill stem or string and is associated with guiding and cutting members arranged in horizontally offset parallelism with the drill string or 15 hole and adapted not only to take up the lateral thrust of the main inclined cutting element but also to act as revolving reamers to ream the hole to some extent as the drill goes down and thus bring about a more or less constant diameter of the hole being drilled.

An object of the invention is to provide a 20 highly efficient cutting bit adapted to cut rapidly and with the parts so arranged as to facilitate the clearing and removing of the chips and loosened material from the bit and the hole.

A further object of the invention relates to the mountings of the revolving cutters in a manner not only to lessen their driving friction but 25 also to provide for the easy detachability and replacement of such parts as are subject to excessive wear, such wear being avoided on the main spindle of the drill head and being borne on nonexpensive parts that may be easily and 30 cheaply replaced.

A further object of the invention is to provide a bit that is efficient in cutting out local hard spots of material and likewise to cut and displace metal parts that may by accident happen in the drill hole.

A further object is to provide a bit adapted to drill straight holes with greater assurance than heretofore had.

Other desirable and meritorious features of 40 the invention will be observed by the descriptions and claims herein.

Reference will be had to the accompanying drawings in which Figure 1 is a vertical, medial section, partly in elevation of a bit embodying my invention. Fig. 2 is a bottom plan view of Fig. 1 with the main cutter elements removed. Fig. 3 is a view similar to Fig. 1 but showing a modified form of cutter and reamer elements. Fig. 4 is a bottom plan view of Fig. 3 but with 50 the main cutter element removed.

Fig. 5 is a plan and Fig. 6 is an elevation of a cap or retainer for the end of the spindle which carries the main cutter element. Fig. 7 is a detached vertical elevation of the bit body as viewed from the same aspect as Fig. 1. Fig.

8 is a front elevation of the modified form shown in Fig. 3, looking from the right thereof.

Fig. 9 is an end view and Fig. 10 an elevation of a bearing bushing sleeve for the spindle which carries the main cutting element. Figs. 11, 12, 5 13, 14, 15 and 16 are sections and plans of toothed cutters and disks forming the main cutter elements.

In the drawings, 1 indicates the shank of the 10 bit body D, the internally threaded portion 2 of the shank being adapted for connection to the drill pipe (not shown). Below the portion 2 there is a bore 3 from which a tubular passage 4 extends downwardly toward the cutting elements 15 in a manner and direction to impinge the drilling fluid or mud that flows down the circulation bore of the drill pipe directly onto the teeth of the bit cutting elements and thus wash them free of detritus, and also to facilitate the circulation in carrying the cuttings up and away 20 from the bottom of the hole.

Bit body D includes a vertical depending leg or portion E which is horizontally offset from shank axis A—A, and is provided with an inclined tubular spindle 5, through the bore 6 25 of which extends a bolt 7 whereby the main cutter F is held to the spindle. In Fig. 1, main cutter F is made up of a plurality of independently rotatable cutter units 11, 12 and 14.

On spindle 5 there is mounted a bearing bushing sleeve 8 and in contact therewith is a set of balls 9 and a set of rollers 10, balls 9 and rollers 10 forming axially spaced antifriction bearings on which is carried the substantially cylindrical cutter element or unit 11, the periphery of which is provided with cutting teeth G. Cutter 11 has a smooth, reduced-diameter, axial extension or cylindrical stud 13 upon which is rotatably mounted a bevel cutter disk 12.

An associated bevel cutter disk 14 is mounted 40 to revolve on a retainer cap or end-piece 15 held in place by the bolt 7. This cap is provided with two projections 16 which extend into notches 17 in the end of spindle 5 and thus it is prevented from revolving on the bolt 7. The bolt 45 7 is held from revolving by a pin 17' passing through the bolt end and the projections 16 of cap 15. This cap 15 abuts against the end of the bearing bushing sleeve 8 and holds it from coming off the spindle 5. A dowel pin 18 fits 50 a socket in leg E and a registering socket in the flange of the bearing bushing sleeve 8, thus preventing the sleeve from revolving on the spindle 5.

The cap 15 is provided with a flange 9 which 55

engages the associate bevel cutter disk 14 and holds it in place and the disk 14 abuts against the main cutter 11 and the bevel cutter disk 12 and holds them in place.

5 The arrangement of cutters 11, 12 and 14 provides for separate renewal of these elements if they become individually worn, while wear on spindle 5 is prevented. The several cutters may thus revolve at their own individual speeds, as 10 induced by contact with the material acted upon.

In the modified form as shown by Fig. 3, the main cutter element is indicated by 20 and is a unitary member shaped in outline like the assembled cutting element of Fig. 1.

15 The main cutters herein shown in assembly outline shape simulate a cone but are not a true cone.

Reamer cutters 21, each rotatable about a vertical axis, are mounted on and depend from the underside of body D above the main cutters F or 20 and in offset but overlying relation thereto, as will be apparent from Figs. 2 and 4. As illustrated in Figs. 1, 3 and 8, the reamers 21 are carried on spindle bolts 22 extending through the flange portion H of the body. The reamers rotate on antifriction rollers 22', and washers 23 are provided to reduce friction and wear between the reamer cutters and the shoulder or undersurface of the body flange. In the form of the 30 invention shown in Figs. 1 and 2, I provide a pair of reaming cutters 21 arranged symmetrically at opposite sides of the vertical plane P—P of the drilling cutter spindle 5, which plane intersects the vertical central axis A—A, see Fig. 1, of the body and shank of the tool. It will be noted that cutters 20 and F are extended inwardly a 35 distance substantially beyond the projected body axis A—A, thus permitting the use of a large diameter cutter having cutting engagement with the bottom of the hole throughout the full radius of the bore. In the form shown in Figs. 3 and 4, three reaming cutters are provided, one pair 21a being positioned at opposite sides of the axial plane P—P of the spindle and set back toward the 40 spindle beyond the positions of the reamers in the form of Figs. 1 and 2. A third reaming cutter 21b is positioned directly opposite the spindle 5 with its vertical axis lying in the spindle plane P—P. In both forms of the invention, the reaming cutters extend within the recess R, defined by the under-surface 30 of the body or its flanged portion H and the inner face of leg E, with the reaming cutters in overlying relation to cutters F and 20 so that the cutter assembly is arranged in 45 compact form within the recess and in balanced relationship with respect to lateral thrusts during drilling operations.

The arrangement of the reamer cutters 21 as spaced apart and above the main cutters F and 60 20, allows clearance for direct and forceful impingement of the descending circulation mud to clear the cuttings from the bit and from the bottom of the hole, a feature of considerable importance.

65 The main cutters, in cutting on one side as they revolve, act as sweeps to brush out the cuttings thus leaving practically no cuttings to be "worked over".

A bit that cuts substantially on one side, as in 70 this invention, must be sustained against lateral thrust and this is provided by the cutter reamers 21. Since these reamer cutters revolve they act like rollers to lessen friction on the driving mechanism. Further, these reamers serve to 75 maintain a full diameter of hole even when some

wear takes place on the main cutting element, which wear would otherwise result in the drilling of a slightly tapered hole.

It is well known that a drill tool that cuts substantially only at one side of its diameter as it 5 revolves and is held firmly in a position of alignment by its body support, cuts more nearly straight holes than a tool cutting at both sides, as it is difficult if not impossible to maintain each side of a double bit so that both cut absolutely 10 the same and thus one side crowds the other and thereby induces a variation in alignment of hole produced. This is especially noticeable in drilling strata which is much inclined.

The arrangement of the invention herein as 15 shown is efficient in cutting straight holes.

It will be understood that it lies within the broader aspects of the invention to provide any suitable means for holding the main cutters in line, and therefore that the showing of vertical 20 and rotatable cutting reamers for this purpose is not to be considered as limitative on this aspect. Where rollers are used (either toothed or plain) their axes may be arranged with respect to the tool axis in the way best suited to give the 25 tool high efficiency in the particular formation being drilled.

What I claim is—

1. In a bit for attachment to a drill pipe, a body member having an integral tubular spindle extending at an incline from the outside downwardly toward the drilling center axis, a bearing bushing sleeve over said spindle and fixed from revolving thereon, roller and ball bearing races on said sleeve, a main rotary toothed cutter 30 mounted on said bearings, a smooth cylindrical projection on said cutter, a beveled cutting toothed disk mounted to revolve on said projection, a cap having a cylindrical portion and fixed at the bottom end of said integral spindle and provided with 35 an annular flange at the end of the cylindrical portion, a beveled cutting toothed disk mounted to revolve on the cylindrical portion of said cap against the flange and in close contact with its adjacent beveled cutting toothed disk, a bolt 40 passing through said cap and through the said integral spindle and adapted to hold said cutter and disks in assembly and in place; in combination with vertically arranged toothed roller reamer cutters mounted on the body to sustain the lateral thrust on the bit and to ream the hole, and a passageway in the body adapted to extend from the drill pipe bore and aligned to impinge circulation fluid upon and thereby clean the said cutting assembly. 45

2. In a bit of the class described, a body member having an integral tubular spindle extending at an incline from the outside downwardly toward the drilling center axis, a bearing bushing sleeve over said spindle and fixed from revolving thereon, roller and ball bearings on said sleeve, a main rotary toothed cutter mounted on said bearings, a smooth cylindrical projection on said cutter, a beveled cutting toothed disk mounted to revolve on said projection, a cap having a cylindrical portion and fixed at the bottom end of said integral spindle and provided with an annular flange at the end of the cylindrical portion, a beveled cutting toothed disk mounted to revolve on the cylindrical portion of said cap against the flange and in close contact with its adjacent beveled cutting toothed disk, a bolt passing through said cap and through the said integral spindle and adapted to hold said cutter and disks in assembly and in place; in combination with vertically ar- 50 55 60 65 70 75 80 85 90 95

ranged toothed roller reamer cutters mounted on the body to sustain the lateral thrust on the bit and ream the hole.

3. In a rotary tool for drilling a well bore, a body, a single leg depending from one side of the body with the inner face of the leg horizontally offset from the vertical axis of the body, the under face of the body and the inner face of the leg defining a recess opening downwardly and outwardly at the other side of the body, a spindle supported by the leg and extending downwardly and inwardly toward the body axis, a roller cutter supported for rotation about the spindle axis, said roller having an exposed, effective cutting edge extending upwardly and radially outwardly from a point substantially in line with said vertical axis toward the outer face of the leg, a portion of said cutter underlying said recess, and a rotatable element mounted on and depending from the underside of the body, said element being disposed within said recess and being rotatable about a substantially vertical axis offset from the body axis at the side opposite the leg, the element overlying said portion of the cutter and extending radially outward for engagement with the wall of the well bore to oppose lateral thrust of the cutter.

4. In a rotary tool for drilling a well bore, a body, a single leg depending from one side of the body with the inner face of the leg horizontally offset from the vertical axis of the body, the under face of the body and the inner face of the leg defining a recess opening downwardly and outwardly at the other side of the body, a spindle supported by the leg and extending downwardly and inwardly toward the body axis, a roller cutter supported for rotation about the spindle axis, said roller having an exposed, effective cutting edge extending upwardly and radially outwardly from a point substantially in line with said vertical axis toward the outer face of the leg, a portion of said cutter underlying said recess, and a pair of angularly spaced rotatable elements mounted on and depending from the under side of the body, each of said elements being disposed within said recess and being rotatable about a substantially vertical axis offset from the body axis at the side opposite the leg, both elements overlying said portion of the cutter and extending radially outwardly for engagement with the well bore to oppose lateral thrust of the cutter.

5. In a rotary tool for drilling a well bore, a body, a single leg depending from one side of the body with the inner face of the leg horizontally offset from the vertical axis of the body, the under

face of the body and the inner face of the leg defining a recess opening downwardly and outwardly at the other side of the body, a spindle supported by the leg and extending downwardly and inwardly toward the body axis, a roller cutter supported for rotation about the spindle axis, said roller having an exposed, effective cutting edge extending upwardly and radially outwardly from a point substantially in line with said vertical axis toward the outer face of the leg, a portion of said cutter underlying said recess, a rotatable element mounted on and depending from the underside of the body, said element being disposed within said recess at a point diametrically opposite said leg and being rotatable about a substantially vertical axis offset from the body axis at the side opposite the leg, and a pair of rotatable elements disposed within said recess at opposite sides of the common axial plane of the cutter and the first mentioned element, each of said pair of rotatable elements being rotatable about a substantially vertical axis, all said elements overlying said portion of the cutter and extending radially outward for engagement with the wall of the well bore to oppose lateral thrust of the cutter.

6. In a rotary tool for drilling a well bore, a body, a single leg depending from one side of the body with the inner face of the leg horizontally offset from the vertical axis of the body, the under face of the body and the inner face of the leg defining a recess opening downwardly and outwardly at the other side of the body, a spindle supported by the leg and extending downwardly and inwardly toward the body axis, a roller cutter supported for rotation about the spindle axis, said roller having an exposed, effective cutting edge extending upwardly and radially outwardly from a point substantially in line with said vertical axis toward the outer face of the leg, a portion of said cutter underlying said recess, and a rotatable element mounted on and depending from the underside of the body, said element being disposed within said recess and being rotatable about a substantially vertical axis offset from the body axis at the side opposite the leg, the element overlying said portion of the cutter and extending radially outward for engagement with the wall of the well bore to oppose lateral thrust of the cutter; there being a circulation passageway extending through said body and opening downwardly into said recess whereby circulation fluid is adapted to be directed from the passageway onto both said cutter and said element.

WALTER ANDREW ABEGG. 55
